UNITED STATES PATENT OFFICE.

A. B. COOLEY, OF PHILADELPHIA, PENNSYLVANIA.

IMPROVEMENT IN MODES OF DISCHARGING PROJECTILES.

Specification forming part of Letters Patent No. 35,587, dated June 17, 1862.

To all whom it may concern:

Be it known that I, A. B. COOLEY, of Philadelphia, Pennsylvania, have invented a Mode of Discharging Projectiles; and I do hereby declare the following to be a full, clear, and exact description of the same, reference being had to the accompanying drawings, and to the letters of reference marked thereon.

My invention consists in a solid cylinder adapted to fit into an orifice in a shot or shell, and combined with a shield to obstruct the injurious products of the ignition of the powder contained between the end of the orifice in the said shot or shell and the end of the cylinder.

In order to enable others to practice my invention, I will now proceed to describe the manner of carrying it into effect.

On reference to the accompanying drawings, which form a part of this specification, Figure 1 is a side view, partly in section, of the shell and the base from which it is discharged; Fig. 2, a sectional plan on the line 12, Fig. 1; and Fig. 3 a rear view of part of Fig. 1.

The shell A has, as regards its external form, an elongated tapering rear, with a pointed head, as seen in Fig. 1. In the tapering rear of the shell is a circular orifice of the same diameter throughout, and adapted to receive the cylindrical stem b, which projects from and forms a part of the base B. In the present instance this base is of a hemispherical form, and has two trunnions, a, which fit in and are guided by projections e e on a block, c, in which is a concave recess, for receiving the hemispherical portion of the base B. A bell-shaped shield, d, surrounds the stem b, the space between the shield and the stem being more than sufficient to freely admit the tapering rear of the shell. The head of the shell has a chamber for containing the charge, which can be exploded by means of the usual time-fuse or by percussion, this chamber being separated by a solid partition, i, from the orifice which receives the stem b. The powder m for discharging the shell is contained between the end of the stem and the end of the orifice in the shell, and this powder may be exploded by means of the usual cannon-primer inserted in the touch-hole x, the shell the moment the discharge occurs taking a course determined by the position to which the stem b has been adjusted.

Between the powder m and the end of the stem intervenes a wad, n, which serves the

twofold purpose of maintaining the powder in its place when the shell is detached from the stem, and of forming, by being compressed, a packing for preventing the escape of explosive gases when the discharge takes place. As the shell leaves the stem b, the smoke and other products of the discharged powder will be forced in a direction contrary to the course of the shell, and would have a tendency to injure the gunners but for the shield d, which forms an effective barrier against the reaction of the injurious products of the ignition of the powder.

I propose in some instances to load the orifice of the shell partly with ordinary powder and partly with the composition with which rockets are charged, a body of this composition being packed into the end of the orifice, and the powder being deposited between the composition and the end of the stem b, the powder being sufficient in quantity to discharge the shell and the composition ignited by the explosion of the powder acting with the same effect as in ordinary rockets, and continuing to propel the shell in the course in which it has been directed by the powder after the force imparted by the latter has been spent.

The base B may be varied in form, and may, with its stem and shield, be hung to a block or carriage in the same manner as ordinary mortars, although I prefer forming the base with a hemispherical rear and allowing it to rest in a concave recess of the block, in which it can be adjusted by means of a worm, y, gearing into teeth w on the base, or by any other suitable appliances. The block c (shown in red lines) presents a solid foundation, with which the base is always in contact, the projections e merely serving as guides and not as bearings for the trunnions.

As the tapering rear of the shell has to resist the force of the powder, great strength of metal is necessary near the point where the charge is deposited. This strength may be increased, and at the same time the shell may be diminished in bulk by the use of wrought-iron bands.

Spiral projections may be made in the cylindrical stem and corresponding spiral grooves in the orifice of the shell should it be desirable to impart a rotary motion to the latter.

I do not desire to claim, broadly, discharging a shot or shell from a solid cylinder ar-

ranged to fit in an orifice in the said shot or shell, as this mode of discharging projectiles is illustrated and described in page 60, volume 60, Mechanics' Magazine, 1854; but

I claim as my invention and desire to secure by Letters Patent—

The solid cylinder *b*, adapted to fit into the shot or shell *A*, and combined with the shield *d*, substantially as and for the purpose herein set forth.

In testimony whereof I have signed my name to this specification in the presence of two subscribing witnesses.

A. B. COOLEY.
